UNITED STATES PATENT OFFICE.

JOSEPH R. COOPER, OF SPARGURSVILLE, OHIO.

OVERCHECKREIN-SPRING.

SPECIFICATION forming part of Letters Patent No. 739,152, dated September 15, 1903.

Application filed July 7, 1902. Serial No. 114,698. (No model.)

To all whom it may concern:

Be it known that I, JOSEPH R. COOPER, a citizen of the United States, residing at Spar-
5 gursville, Ross county, State of Ohio, have in-
vented an Overcheckrein-Spring, of which the
following is a specification.

My invention relates to new and useful im-
provements in overcheckrein-springs; and its
object is to provide a simple, durable, and
10 inexpensive device of this character which is
ornamental, can be readily secured in proper
position, and renders an overcheckrein more
durable and less injurious.

With the above and other objects in view
15 the invention consists in the novel construc-
tion and combination of parts hereinafter
more fully described and claimed, and illus-
trated in the accompanying drawings, show-
ing the preferred form of my invention, and
20 in which—

Figure 1 is a plan view of the spring. Fig.
2 is a side elevation thereof, and Fig. 3 is a
side elevation of the device with the springs
expanded.

25 Referring to the figures by numerals of ref-
erence, 1 is a loop, one side of which is loosely
arranged within a plate 2, to which are se-
cured the ends of coiled springs 3. Within
30 this plate is also loosely mounted the central
portion of a U-shaped rod 4, the ends of which
are looped, as shown at 5, and are slidably
mounted upon a similar U-shaped rod 6, the
ends 7 of which are looped and slidably mount-
35 ed upon rod 4. The intermediate portion of
rod 6 is loosely mounted within the plate 8,
which is bent upon itself and secured at op-
posite sides of a flexible extension 9, prefer-
ably formed of leather and having an aper-
ture 10 therein. The springs 3 are also se-
40 cured to plate 8, and it is therefore obvious
that when loop 1 is drawn away from said
plate 8 springs 3 will be expanded and the
looped ends 5 and 7 of rods 4 and 6 will slide

upon the rods on which they are mounted and
serve to guide and prevent twisting of the 45
springs. A checkrein is adapted to be se-
cured to loop 1 in any suitable manner, and
the hook on a harness-saddle is adapted to
project into the aperture 10, formed within
the flexible extension 9. As this extension 50
is formed of leather or similar material, it is
obvious that the hook of the saddle will not
be injured thereby. The device is extremely
simple and inexpensive in construction and
can be readily attached to ordinary check- 55
reins.

In the foregoing description I have shown
the preferred form of my invention; but I do
not limit myself thereto, as I am aware that
modifications may be made therein without 60
departing from the spirit or sacrificing any
of the advantages thereof, and I therefore re-
serve the right to make such changes as fairly
fall within the scope of my invention.

Haying thus described the invention, what 65
is claimed as new is—

In a device of the character described, the
combination with a plate bent upon itself and
a flexible extension secured within the plate,
of a second plate bent upon itself, a loop rev- 70
olubly mounted therein, a U-shaped rod rev-
olubly mounted in each plate, loops integral
with the ends of the rods and slidably mount-
ed upon the oppositely-disposed rod, whereby
a substantially rectangular frame is formed, 75
and coiled springs parallel with and between
the sides of the rods, the ends of the springs
being secured to the inner edges of the plates.

In testimony whereof I have signed my
name to this specification in presence of two 80
subscribing witnesses.

JOSEPH R. COOPER.
